(57) **CLAIM**

The ornamental design for a tire rim protector, as shown and described.

DESCRIPTION

FIG. 1 is a front elevational view of a tire rim protector embodying our design, the tire being shown in dotted lines forms no part of our design;

FIG. 2 is a rear elevational view of the tire rim protector as shown in FIG. 1;

FIG. 3 is a right side elevational view of the tire rim protector as shown in FIG. 1, the left side elevational view being a mirror image thereof;

FIG. 4 is a top plan view of the tire rim protector as shown in FIG. 1;

FIG. 5 is a bottom plan view of the tire rim protector as shown in FIG. 1; and,

FIG. 6 is a cross-sectional view of the tire rim protector as shown in FIG. 2 as seen along lines 6—6.
